US0D1108889S

(12) United States Design Patent (10) Patent No.: US D1,108,889 S
(45) Date of Patent: * Jan. 13, 2026

(54) PAPER CUP

(71) Applicant: RES LABS Inc., Gimpo-si (KR)

(72) Inventor: Cheolhee Lee, Seoul (KR)

(73) Assignee: RES LABS INC., Gimpo-si (KR)

() Term: 15 Years

(21) Appl. No.: 35/521,981

(22) Filed: Feb. 14, 2024

(80) Hague Agreement Data

Int. Filing Date: Feb. 14, 2024

Int. Reg. No.: DM/238255

Int. Reg. Date: Feb. 14, 2024

Int. Reg. Pub. Date: Aug. 16, 2024

(30) Foreign Application Priority Data

Aug. 24, 2023 (KR) 30-2023-0033137

(51) LOC (15) Cl. 07-01

(52) U.S. Cl.

USPC D7/510; D7/512

(58) Field of Classification Search
